JET PROPULSION MEANS FOR BOATS

Lewis B. Nickles, Livonia, Mich.

Application April 20, 1955, Serial No. 502,596

1 Claim. (Cl. 115—12)

The present invention relates to jet propulsion of boats and has among its objects to greatly increase the efficiency of such means of propulsion by syphonic action.

Heretofore jet propulsion for boats has been accomplished by means of jets of water discharged rearwardly but such means while producing propulsion, is low in efficiency and is open to other objections.

Among the objects of the present invention is to utilize them in such manner and in means that greatly increases such efficiency.

Another object is to provide jet propulsion using stationary jets for both forward and reverse movement.

Still other objects will readily occur to those skilled in the art upon reference to the following description and the accompanying drawings in which—

Figure 1 is a more or less diagrammatic plan view of a boat hull having installed therein the propelling means.

Figure 2 is a sectional view longitudinally of one of the propulsion devices.

Figure 3 is a front elevation of the intake screen.

Figure 4 is a side elevation of the same.

Figure 5 is an end elevation of Figure 2.

In the drawing, the outline of a boat hull is indicated at A with its prow at B and its stern at C showing a pair of rudders D. Inside of the hull A there is shown at 19 a suitable motor, preferably an internal combustion engine coupled to a pump 11, preferably a centrifugal pump having its intake 12 connected to a screen casing 13 and its delivery 14 connected to a manifold 15.

The manifold 15 is shown as provided with four branches 16 connected to four valve casings 17, 18, 19 and 20, the first three of these being conventional two-way valves while the fourth 20 is a one-way valve.

Near the stern of the boat is located a manifold system consisting of two manifolds 21 and 22 extending crosswise of the boat and two others 23 and 24, one 23 extending diagonally from the right end of manifold 21 to the left end of manifold 22. The other 24 extends from the left end of manifold 21 to the right end of manifold 22. These four manifolds are connected to the valves 17 and 18 as follows:

Manifold 21 is connected through a conduit 25 to the right of valve 17. Manifold 22 is connected through conduit 26 to the left end of valve 17. Manifold 23 is connected through conduit 27 to the left end of valve 18. Manifold 24 is connected through conduit 28 to the right end of valve 18. The two manifolds 21 and 22 at their ends are connected through the hull of the boat to injector nozzles 21A, 21B and 22A, 22B respectively which nozzles are also open to the ends of the manifolds 23 and 24.

Of the several nozzles, those at 21A and 22B are located within and near the ends of a tube or tunnel 30 of the diameter of which is shown as about twice that of the injector nozzle opening, and which is open at both ends and arranged longitudinally of the hull at a sufficient distance from the keel E to be above the bottom of the keel. The other nozzles 21B and 22A are arranged similarly in a second similar tube 31, on the other side of keel E.

2

While the ratio of the diameter of the tunnel and nozzle is shown and described above as about 2 to 1, it may be greater or less, depending upon desired characteristics.

Further, the nozzles 21A and 21B are directed forwardly of the boat while the nozzles 22A and 22B are directed rearwardly.

In operation, with the motor 10 running but without propulsion in either direction, the pressure built up by the pump is relieved by means of a suitable tensioned safety valve 32 which discharges into the casing 13 in front of and across the inlet screen. This valve 32 also functions to relieve the pressure built up in the manifold 15 when any of the valves 17 to 19 is moved from one open position to the other—both openings will be closed momentarily during the transition.

In the forward propulsion of the boat, the valve 18 will be in its centered position with the conduits 27 and 28 closed and valve 17 moved to open conduit 26 and closed conduit 25.

The full pump delivery will be from the injector nozzles 22A and 22B and will cause the siphoning of a considerably greater quantity of water through the tunnels 30 and 31 and therefore a greater reaction on the boat.

If it is desired to reverse the boat movement, the valve 17 will be moved to close conduit 26 and open conduit 25 so that the pump delivery will be through nozzles 21A and 21B reversing the flow through tunnels 30 and 31.

The steering of the boat is preferably done mainly by means of the rudders D but if it is desired to make a tight turn, the valve 17 is centered and closed and the valve 18 put into operation. This valve 18 directs the water from manifold 15, through one or the other of conduits 27 and 28. Conduit 27 leads to manifold 23 and to nozzles 21A and 22A which tend to turn the prow to the right. Conduit 28 leads to manifold 24 and nozzles 21B and 22B which tend to turn the prow to the left.

The valve 19 is used when it is desired to move the boat laterally, and controls flow of water through the conduits 40 and 41, each of which terminates in a pair of widely spaced nozzles 43 discharging laterally of the boat.

The valve 20 is a one-way valve which may be used when it is desired to utilize the pump delivery for any purpose other than propulsion, such for example, as hose attachment.

The water inlet for the pump, as above mentioned, will be through a casing 13 divided by a screen 13A and having the front 13B open with a closed compartment 13C behind the screen. The pump inlet 12 will open to this compartment while the discharge 32A from valve 32 will be in front of and laterally across the screen in order to clear away any accumulation of debris.

In order to control the direction of flow of water in the several manifolds each is provided with an outwardly opening check valve 38 between the nozzle ends and the conduit leading water into the manifold.

I claim:

Boat propulsion means comprising a pair of tubular water tunnels fixed to the outer wall of the boat hull parallel to the keel and below the water line, an injector nozzle within and adjacent to each end of each tunnel and arranged to discharge toward the tunnel end adjacent thereto, and means for supplying water under pressure to selected ones of said nozzles, said supply means comprising a pump having its delivery connected to a plurality of manifolds, one of which is connected to those two nozzles at the forward ends of the tunnels, a second one of which is connected to the nozzles at the rearward ends of the tunnels, a third manifold being connected to one forward and one rearward nozzle and a fourth manifold being connected to the other forward and the other rearward nozzles, a check valve in each manifold adjacent

each nozzle and opening toward said nozzle, and valve means for directing pump delivery to a selected one of the manifolds.
